[57] CLAIM

The ornamental design for a lamp base, as shown and described.

DESCRIPTION

FIG. 1 is a perspective view of the lamp base showing my new design; and,

FIG. 2 is a front elevation view of the lamp base of FIG. 1.
